TEMPERATURE ALARM DEVICE

Cecil R. Wood, Green Mountain Falls, Colo.

Application March 13, 1934, Serial No. 715,328

1 Claim. (Cl. 116—106)

My invention relates to temperature alarm devices and my object is to provide a temperature controlled releasing mechanism for devices of this character.

5 Figure 1 represents a side elevation of the device, partly in section; Fig. 2, a cross sectional elevation through the center of the device, the electrical contacting means being removed; Fig. 3, a cross section end elevation of the device on the line 3—3 in Fig. 2, drawn to an enlarged scale; Fig. 4, a cross sectional elevation showing the balls wholly within the chamber 15; Fig. 5, a cross sectional elevation of the rod 11, through the chamber 15; and Fig. 6, a cross sectional elevation of the rod 11 showing the fusible member 17 disposed in chamber 15.

Although I show the preferred embodiment of my invention, I do not thereby limit myself to the precise details shown, but wish it understood that, within the scope of what hereinafter is claimed, various changes in the details may be made without departing from the spirit of the invention.

A cartridge holding member 1, provided with a cartridge chamber 2, is disposed in one end of the housing 3 and held in position by a screw 4 which also holds the strap 5 provided with a hole 6. A removable guide member 7 is disposed in the opposite end of housing 3 and held in position by a screw 8 which also holds a strap 9 provided with a hole 10. A rod 11 is slidably disposed in guide member 7 and provided with a pointed end 12 and a guide shoulder 13. An open helical spring 14 is disposed on rod 11 between guide shoulder 13 and guide member 7. A chamber 15 extends diametrically through rod 11 and communicates with exit channels 16. A fusible spacer member 17 is disposed in chamber 15 and balls 18 are disposed in chamber 15 so as to rest against fusible spacer member 17 and to be held apart thereby, so as to protrude beyond the periphery of rod 11 to form stops which cooperate with guide member 7 to prevent rod 11 from sliding through guide member 7 and to hold spring 14 in a compressed position.

A tube 20 of insulation material is disposed on rod 11 and secured thereto by a screw 21. A terminal 22 is secured on tube 20 by a screw 23.

A terminal 24 is secured to housing 3 by a screw 25 and is adapted to cooperate with terminal 22 to close an electrical circuit formed by wires 26—27 and the source of electricity to which said wires are connected. The wires 26—27 may be connected to a bell system or other electrically actuated devices.

In setting the device, the interior mechanism is removed. Guide member 7 is pressed against spring 14 beyond chamber 15; fusible spacer

member 17 and balls 18 are disposed in chamber 15 and guide member 7 is allowed to cooperate with balls 18 to hold spring 14 in the compressed position. When thus assembled the interior mechanism is replaced and held in position by 5 screw 8 and guide member 7. A blank cartridge C is disposed in chamber 2 and member 1 returned to housing 3 and held in position by screw 4. The device is secured to a wall or other support by screws extending through holes 6—10 in 10 straps 5 and 9, respectively.

When the temperature in the vicinity of the device reaches a predetermined point, as for example 150 degrees F., the fusible spacer member 17 melts and runs out through exit channels 16, 15 thereby allowing balls 18 to be pressed into chamber 15 by guide member 7, permitting spring 14 to force rod 11 forward against the cap in cartridge C and thereby explode cartridge C. At the same time that the pointed end 12 of rod 11 20 strikes the cartridge cap, terminals 22 and 24 contact and close an electrical circuit to operate an electrical alarm system, when such an alarm system is associated with my device.

The expanded gases resulting from the explosion of the cartridge C travel through pipe 28 to a general alarm system, when such alarm system is associated with my device.

It is my purpose to use my device in association with an electric alarm system, or with a 25 general alarm system which I have invented to be operated by the expansion of the gases incident to the explosion of the cartridge, or with both alarm systems. When used without said 30 systems, I employ the cartridge C which is discharged by the action of the device, the report of the 35 explosion being sufficiently loud to give the alarm.

I claim:

In a temperature alarm device, the combination of a guide member adapted to be secured to a stationary object; a rod slidably disposed in said guide member and provided with a transverse chamber extending diametrically therethrough, 45 and exit channels communicating with said chamber; a fusible spacer member disposed in said chamber; and a stop member disposed in said chamber adjacent to each end of said spacer member so as to be held apart by said spacer member so that said stop members normally protrude out of said chamber to form stops which 50 cooperate with said guide member to prevent said rod from sliding forward through said guide member until said spacer member melts and permits said stop members to recede within said chamber 55 and clear said guide member.

CECIL R. WOOD.
